BLANK HOLDING MEANS FOR SHEET METAL PRESSES

Filed Nov. 6, 1926

2 Sheets-Sheet 2

Inventor:
John Nelson

UNITED STATES PATENT OFFICE.

JOHN NELSON, OF CHICAGO, ILLINOIS, ASSIGNOR TO MARQUETTE TOOL & MANUFACTURING COMPANY, OF CHICAGO, ILLINOIS, A CORPORATION OF ILLINOIS.

BLANK-HOLDING MEANS FOR SHEET-METAL PRESSES.

Application filed November 6, 1926. Serial No. 146,629.

This invention relates to improvements in blank holding means for sheet metal drawing presses, and one of the objects of the invention is to provide improved means whereby 5 a substantially uniform or unvarying pressure will be provided throughout substantially the entire length of the stroke of the press, and which means will also eliminate back lash.

10 A further object is to provide improved means for returning the pin or pressure plate to restore the draw ring or blank holding member to its initial or starting position.

To the attainment of these ends and the 15 accomplishment of other new and useful objects as will appear, the invention consists in the features of novelty in substantially the construction, combination and arrangement of the several parts hereinafter more 20 fully described and claimed and shown in the accompanying drawings illustrating this invention and in which,

Figure 1 is a front elevation of a portion 25 of a press showing a blank holding means constructed in accordance with the principles of this invention, applied thereto, the blank holding means and portions of the press being in section, the press being shown in its starting position.

30 Figure 2 is a view similar to Figure 1, showing the parts in another position.

Figure 3 is a detail sectional view taken on line 3—3, Figure 2.

Figure 4 is a detail sectional view taken 35 on line 4—4, Figure 2.

Referring more particularly to the drawings the numeral 10 designates generally the body of a press upon which is mounted a bed plate 11 which supports a die 12, with which 40 another die 13 connected with the ram or slide 14 co-operates. The ram 14 is reciprocable in the guideways by means of a link 15 connected with a crank shaft 16, the latter being rotated in any suitable manner.

45 All the above referred to parts may be of the ordinary and well known construction.

Co-operating with the die 12 and encompassing the same is a draw ring or blank holding member 17, which is supported by 50 the usual pins 18 which pass through the bed

plate 11 and engage and rest upon a pin or pressure plate 19 below the bed plate 11.

Supported below the bed plate at any suitable distance and by means of suspension or hanger rods 20, is a cylinder 21, which is 55 preferably open at its top, the cylinder being provided with a circumferential flange or lugs 22, through which the ends of the rods 20 pass. The cylinder is supported by these rods preferably by means of nuts 23 60 which are threaded upon the ends of the rods and the nuts co-operate preferably with shoulders 24 on the rods 20 for holding the cylinder 21 in position. Reciprocable in the cylinder 21 is a piston 25 which has an opening therethrough forming a valve seat 26. The piston is connected with the pin plate 19 to reciprocate therewith preferably by means of bars or rods 27 so that when the pin plate 19 is depressed the piston 25 will 70 be lowered in the cylinder 21.

Within the cylinder 21 and normally beneath the piston 25 is a liquid 28 which is non-compressible. The piston 25 may, if necessary, be provided with packing 29. 75

Interposed between the pin plate 19 and the flange or lugs 22 on the cylinder 21, is a resilient member 30, preferably in the form of a coil spring, one end of which engages the pin plate and the other end engages and 80 rests upon the lugs or flange 22, being coiled about the upper part of the cylinder 21. This resilient member 30 tends normally to hold the pin or pressure plate 19 against the bottom of the bed plate 11 or in a position to 85 support the blank holding member or draw ring 17 so that the upper face will normally stand substantially flush with the upper face of the die 12.

When the ram 14 descends, causing the die 90 13 to depress the blank holding member or draw ring 17, the pins 18 will move the pin plate 19 downwardly against the stress of the spring 30.

When the ram ascends the spring 30 will 95 return the pin plate.

Depending from the piston 25 and preferably passing through the bottom of the cylinder 21 is an extension 31 which forms a guide for the stem 32 of the valve 33, 100

which co-operates with the valve seat 26 in the piston 25 to close the opening through the piston.

The valve is held to its seat in the piston 25 under normal conditions by means of a spring 34, preferably a coil spring, one end of which rests against the valve 33 and is coiled about a projection 35 on the valve. The other end of the spring 34 rests against 10 the bed plate and exerts its pressure upon the valve to normally seat the same.

Packing 36 may be provided in the guide 31 through which the stem 32 of the valve passes, and packing 37 may also be provided 15 for the extension 31 where it passes through the bottom of the cylinder.

The piston 25 is provided with an additional opening 38 which is closed by a valve 39 opening in a direction opposite to the 20 direction in which the valve 33 opens. The valve 39 is normally held seated by means of a spring 40, the valve 39 operating when the piston 25 is lowered in the cylinder 21 against the liquid 28 therein, to close the 25 opening 38, and when the piston 25 is elevated, the valve 39 will be opened by suction created in the cylinder 21 beneath the piston 25.

This valve 39 is provided so as to permit 30 the liquid, which passes through the opening in the piston 25, when the valve 33 is unseated, to return to the bottom side of the piston when the valve 33 is seated and on the upstroke of the piston 25.

35 The extension 31 on the piston 25 is provided with ports or openings 41, which form communication between the cylinder 21 and a chamber 42, beneath the valve 33, so that when the piston 25 is lowered against the 40 liquid in the cylinder 21 beneath the piston, the liquid will flow through the openings 41 into the chamber 42 so as to act upon the lower face of the valve 33 to unseat the latter. These ports 41 may be of any desired size, but the smaller the ports are the 45 weaker the spring or resilient member 34 may be to procure the same resistance. The valve stem 32 projects through and for a considerable distance beyond the extremity of the extension 31 and is provided with a threaded extremity 43 upon which a nut 44 is threaded. A spring 45 encompasses the valve stem 32 between the end of the extension 31 and the nut 44 and operates upon the valve 33 to yieldingly hold the 55 valve against its seat 26. If desired, a lock nut 46 may be provided on the valve stem.

From this construction it will be manifest 60 that as the pin plate 19 is depressed the pressure of the resilient member or spring 30 will be increased while the pressure of the spring or resilient member 34 will be decreased. Therefore, the springs 30 and 34 must equalize each other and maintain the 65 pressure on the draw ring or blank holding

member 17 substantially constant. That is, the springs must be in the same relative proportion of pressure at all times.

By adjusting the nut 44 upon the valve stem 32 the stress of the spring 45 may be 70 varied and in this manner the degree of pressure upon the liquid 28 in the cylinder 21 which is necessary to unseat the valve 33, may be controlled at will.

In operation and when the ram 14 descends 75 and engages the blank or work 47, the blank will be gripped between the draw ring or blank holding member 17 and the die 13.

A further lowering of the ram causes the draw ring or member 17 to descend against 80 the pressure of the spring 30 and the pressure of the piston 25 against the liquid 28 in the cylinder 21. This will lower the piston in the cylinder and the piston will carry with it the valve 33, causing the spring 34 to be 85 weaker while the stress of the spring 30 becomes stronger. The spring 34 in conjunction with the resistance liquid pressure will then equalize the spring 30.

As the piston descends against the non- 90 compressible liquid 28 in the cylinder 21, the liquid will be forced through the ports 41 against the valve 33 to unseat the latter against the stress of the springs 34 and 45, the liquid escaping to the top side of the 95 piston 25 within the cylinder 21.

The portion of the cylinder above the piston serves as a trap to catch the overflow of liquid.

When the piston 25 is at the bottom of 100 its stroke and the ram ascends the spring 30 will return the pin plate 19 and draw ring 17 to their normal or initial positions. The draw ring or blank holding member 17 will follow the die 13 and the spring 30 maintains 105 the draw ring or blank holding member 17 in contact with the die 13.

When the piston 25 returns or is elevated 110 a vacuum will be created under the piston in the cylinder 21, which operates to suck the valve 39 open, thereby allowing the liquid on the top side of the piston 25 to run back into the cylinder beneath the piston. The spring 40 is only sufficient in strength 115 to maintain the valve 39 seated so that gravity, weight of the valve 39, and weight of the liquid on the top side of the piston 25 will assist in opening the valve 39 when the piston 25 is elevated.

The spring 45 is always maintained under 120 a constant pressure and this pressure may be determined and set, according to the pressure which it may be desired or determined is necessary to unseat the valve 33 and constitutes the entire means for regulating the 125 pressure against which the pin plate 19 operates, because as stated, it regulates the amount of pressure required to displace or unseat the valve 33.

Upon the return stroke of the press the 130

pressure of the liquid or the resistance in the cylinder is overcome by the escape of the liquid through the opening in the piston 25 and the spring 30 is the only force tending to return the piston and pin plate.

The springs 34 and 45 do not act to exert any return pressure.

The spring 34 has, on the contrary, a tendency to slightly retard the return of the 10 pin plate in opposition to the action of the spring 34. The action of the spring 34 depends upon the size of the ports controlled by the valve 33.

With this construction there will be maintained a substantially constant or uniform 15 pressure throughout substantially the entire stroke of the ram, and back lash will be prevented because of the two springs 30 and 34 working in opposition to each other. The 20 liquid 28 in the cylinder 21 will cause a resistance to the operation of the pin plate but no back pressure to return the pin plate.

As the draw ring or blank holding member 17 returns it will operate as a stripper 25 to remove the cup or form which has been shaped over the die 12.

While the preferred form of the invention has been herein shown and described, it is to be understood that various changes may 30 be made in the details of construction and in the combination and arrangement of the several parts, within the scope of the claims, without departing from the spirit of this invention.

35 What is claimed as new is:—

1. A drawing press including a blank holder, means for resisting the movement of said blank holder, said means embodying a resiliently yielding element reacting upon the blank holder, and fluid pressure means also yieldingly resisting the movement of the said blank holder, the said resilient element also operating to return the blank holder after the drawing operation.

45 2. A drawing press including a blank holder, means for resisting the movement of said blank holder, said means embodying a resiliently yielding element reacting upon the blank holder, fluid under pressure greater than atmospheric for also yieldingly resisting the movement of the said blank holder, the said resilient element also operating to return the blank holder after the drawing operation, and means for varying 50 at will the said fluid pressure.

3. A drawing press including a blank holder, means for resisting the movement of said blank holder and for maintaining a substantially unvarying pressure of the 55 blank holder throughout substantially the entire stroke of the press, said means embodying a resiliently yielding element and fluid under pressure greater than atmospheric for also yieldingly resisting the movement of the blank holder, and means for

varying at will the pressure of one of the resistance creating means.

4. A drawing press including a blank holder, and means for resisting the movement of said blank holder and for maintaining a substantially unvarying pressure of the blank holder throughout substantially the stroke of the press, said means embodying two independent and different types of means both operating to yieldingly resist 70 the movement of the said blank holder, one only of said means being operable to return the blank holder.

5. A drawing press including a blank holder, means for resisting the movement of 80 said blank holder and for maintaining a substantially unvarying pressure of the blank holder throughout substantially the stroke of the press, said means embodying two independent and different types of 85 means both operating directly upon the said blank holder for yieldingly resisting the movement thereof, one only of said means being operable to return the blank holder, and means for varying at will the pressure 90 of the other of the said resistance creating means.

6. A drawing press including a blank holder, and means for resisting the movement of said blank holder and for maintaining a substantially unvarying pressure of the blank holder throughout substantially the stroke of the press, said means embodying a resiliently yielding element and fluid under pressure greater than atmospheric and 100 operating directly upon the said blank holder for yieldingly resisting the movement thereof, said resiliently yielding element being also operable to return the blank holder, and means for varying at will the said fluid 105 pressure.

7. A drawing press including a blank holder, means for resisting the movement of said blank holder and for maintaining a substantially unvarying pressure of the 110 blank holder throughout substantially the stroke of the press, said means embodying a resiliently yielding element and fluid pressure means both acting directly upon the said blank holder, means for counterbalancing the said resiliently yielding means, said resiliently yielding element being also operable to return the blank holder, and means for varying at will the said fluid pressure.

8. A drawing press including a blank holder, means for resisting the movement of said blank holder and for maintaining a substantially unvarying pressure of the blank holder throughout substantially the stroke of the press, said means embodying a resiliently yielding element and fluid pressure means both acting directly upon the said blank holder, resiliently yielding means operating in opposition to the first recited 125 resiliently yielding means, said resiliently 130

yielding element being also operable to return the blank holder, and means for varying at will the said fluid pressure.

9. A drawing press including a blank holder, and means for resisting the movement of the blank holder, said means embodying a resiliently yielding element and fluid pressure means both acting directly upon the blank holder, and resiliently yielding means operating in opposition to the first recited resiliently yielding means for controlling the action of the said fluid pressure means.

10. A drawing press including a blank holder, means for resisting the movement of the blank holder, said means embodying a resiliently yielding element and fluid pressure means both acting directly upon the blank holder, resiliently yielding means operating in opposition to the first recited resiliently yielding means for controlling the action of the said fluid pressure means, and means for varying at will the said fluid pressure.

11. A drawing press including a blank holder, means for resisting the movement of the blank holder, said means embodying a resiliently yieldable element and fluid pressure means both acting directly upon the blank holder, said fluid pressure means embodying a cylinder and piston movable relatively one with relation to the other, a valved passage through the piston, and resiliently yielding means for controlling the operation of said valve with relation to the piston.

12. A drawing press including a blank holder, means for resisting the movement of the blank holder, said means embodying a resiliently yieldable element and fluid pressure means both acting directly upon the blank holder, said fluid pressure means embodying a cylinder and piston movable relatively one with relation to the other, a valved passage through the piston, and resiliently yielding means operating in opposition to the first recited resiliently yielding means for controlling the operation of said valve with respect to the piston.

13. A drawing press including a blank holder, means for resisting the movement of the blank holder, said means embodying a resiliently yieldable element and fluid pressure means both acting directly upon the blank holder, said fluid pressure means embodying a cylinder and piston movable relatively one with relation to the other, a valved passage through the piston, and resiliently yielding means for controlling the operation of said valve with relation to the piston, the first recited resiliently yielding means only, operating to return the said blank holder.

14. A drawing press including a blank

holder, means for resisting the movement of the blank holder, said means embodying a resiliently yieldable element and fluid pressure means both acting directly upon the blank holder, said fluid pressure means embodying a cylinder and piston movable relatively one with relation to the other, a valved passage through the piston, resiliently yielding means for controlling the operation of said valve with relation to said piston, and means for varying at will the said fluid pressure.

15. A drawing press including a blank holder, means for resisting the movement of the blank holder, said means embodying a resiliently yielding element and fluid pressure means both operating directly upon the blank holder, said fluid pressure means embodying a cylinder and piston one of which is stationary and the other being connected with the said blank holder for movement therewith, there being a passage through the piston for liquid, a valve for controlling said passage and against which valve the fluid under pressure acts to unseat the valve, and resiliently yielding means tending normally to seat the valve.

16. A drawing press including a blank holder, means for resisting the movement of the blank holder, said means embodying a resiliently yielding element and fluid pressure means both operating directly upon the blank holder, said fluid pressure means embodying a cylinder and piston one of which is stationary and the other being connected with the said blank holder for movement therewith, there being a passage through the piston for liquid, a valve for controlling said passage and against which valve the fluid under pressure acts to unseat the valve, resiliently yielding means tending normally to seat the valve, the last recited resiliently yielding means operating in opposition to the first recited resiliently yielding means, and means for varying at will the fluid pressure necessary to unseat said valve.

17. A drawing press including a blank holder, means for resisting the movement of the blank holder, said means embodying a resiliently yielding element and fluid pressure means both operating directly upon the blank holder, said fluid pressure means embodying a cylinder and piston one of which is stationary and the other being connected with the said blank holder for movement therewith, there being a passage through the piston for liquid, a valve for controlling said passage and against which valve the fluid under pressure acts to unseat the valve, resiliently yielding means tending normally to seat the valve, additional means for yielding seating and maintaining said valve seated, and means for varying at will the stress of the said additional means to vary

the fluid pressure necessary to unseat said valve, the said additional means being carried entirely by the valve.

18. A drawing press including a blank holder and means for resisting the movement of the blank holder, said means embodying a resiliently yielding element and fluid pressure means operating directly upon the blank holder, said fluid pressure means embodying a cylinder and piston one of which is stationary, means connecting the other with the blank holder for movement therewith, there being a passage through the piston for fluid, a valve carried by the piston for closing said passage, resiliently yielding means independent of the piston and tending normally to seat the valve, additional means carried by the piston and operating to yieldingly seat said valve, and means for varying at will the stress of the said additional means whereby the degree of fluid pressure necessary to unseat said valve with respect to the piston may be varied at will.

19. A drawing press including a blank holder and means for resisting the movement of the blank holder, said means embodying a resiliently yielding element and fluid pressure means operating directly upon the blank holder, said fluid pressure means embodying a cylinder and piston one of which is stationary, means connecting the other with the blank holder for movement therewith, there being a passage through the piston for fluid, a valve carried by the piston for closing said passage, resiliently yielding means independent of the piston and tending normally to seat the valve, additional means carried by the piston and operating to yieldingly seat said valve, means for varying at will the stress of the said additional means whereby the degree of fluid pressure necessary to unseat said valve with respect to the piston may be varied at will, an additional passage through the piston, and a valve for controlling the last recited passage.

20. A drawing press including a blank holder and means for resisting the movement of the blank holder, said means embodying a resiliently yielding element and fluid pressure means operating directly upon the blank holder, said fluid pressure means embodying a cylinder and piston one of which is stationary, means connecting the other with the blank holder for movement therewith, there being a passage through the piston for fluid, a valve carried by the piston for closing said passage, resiliently yielding means independent of the piston and tending normally to seat the valve, additional means carried by the piston and operating to yieldingly seat said valve, means for varying at will the stress of the said additional means whereby the degree of

fluid pressure necessary to unseat said valve with respect to the piston may be varied at will, an additional passage through the piston for liquid to pass, and resiliently yielding means for controlling the last said valve, said valves operating in opposite directions with respect to each other. 70

21. A drawing press including a blank holder and means for resisting the movement of the blank holder, said means embodying a resiliently yielding element and fluid pressure means both operable directly upon the blank holder, said fluid pressure means embodying a cylinder and piston one of which is stationary and the other connected with the blank holder for movement therewith, there being a passage through the piston, a valve for closing the passage, a guide on the piston, a stem on the valve passing through the guide and extending therebeyond, a resiliently yielding element disposed between the valve and stem for seating the valve, means for varying the stress of the last recited resiliently yielding element, and an additional resiliently yielding element independent of the valve and operating to seat the valve.

22. A drawing press including a blank holder and means for resisting the movement of the blank holder, said means embodying a resiliently yielding element and fluid pressure means both operable directly upon the blank holder, said fluid pressure means embodying a cylinder and piston one of which is stationary and the other connected with the blank holder for movement therewith, there being a passage through the piston, a valve for closing the passage, a guide on the piston, a stem on the valve passing through the guide and extending therebeyond, a resiliently yielding element disposed between the valve and stem for seating the valve, means for varying the stress of the last recited resiliently yielding element, and an additional resiliently yielding element independent of the valve and operating to seat the valve, the first and last recited resiliently yielding elements operating in opposition to each other. 95 100 105 110

23. A drawing press including a blank holder and means for resisting the movement of the blank holder, said means embodying a resiliently yielding element and fluid pressure means both operable directly upon the blank holder, said fluid pressure means embodying a cylinder and piston one of which is stationary and the other connected with the blank holder for movement therewith, there being a passage through the piston, a valve for closing the passage, a guide on the piston, a stem on the valve passing through the guide and extending therebeyond, a resiliently yielding element disposed between the valve and stem for seating the valve, means for varying the 115 120 125 130

stress of the last recited resiliently yielding element, an additional resiliently yielding element independent of the valve and operating to seat the valve, there being an additional passage through the piston, and a resiliently yielding valve for controlling the last said passage.

24. A drawing press including a blank holder and means for resisting the movement of the blank holder, said means embodying a resiliently yielding element and fluid pressure means both operable directly upon the blank holder, said fluid pressure means embodying a cylinder and piston one of which is stationary and the other connected with the blank holder for movement therewith, there being a passage through the piston, a valve for closing the passage, a guide on the piston, a stem on the valve passing through the guide and extending therebeyond, a resiliently yielding element disposed between the valve and stem for seating the valve, means for varying the stress of the last recited resiliently yielding element, an additional resiliently yielding element independent of the valve and operating to seat the valve, there being an additional passage through the piston, and a resiliently yielding valve for controlling the last said passage, the said valves operating in opposition to each other.

25. A drawing press including a blank holder and means for resisting the movement of the blank holder, said means embodying a resiliently yielding element and a self-contained fluid pressure means both acting directly upon the blank holder, and resiliently yielding means operating in opposition to the first recited resiliently yielding means for controlling the action of the said fluid pressure means.

26. A drawing press including a blank holder and means for resisting the movement of the blank holder, said means embodying a resiliently yielding element and a self-contained fluid pressure means both acting directly upon the blank holder, said fluid pressure means embodying a cylinder and piston relatively movable, said cylinder containing a predetermined supply of fluid transferable back and forth to opposite sides of the piston, said fluid acting on one side of the piston to create a resistance pressure, means for transferring the fluid to the other side of the piston, and means controlled by the fluid pressure for controlling such transfer of the fluid.

27. A drawing press including a blank holder and means for resisting the movement of the blank holder, said means embodying a resiliently yielding element and a self-contained liquid pressure means both acting directly upon the blank holder, said liquid pressure means embodying a cylinder and piston relatively movable, said cylinder

containing liquid acting on one side of the piston to create a resistance pressure, means for transferring the liquid to the other side of the piston, means controlled by the liquid pressure for controlling such transfer of the liquid, and additional means operating to automatically control the transfer of the liquid back to the first recited side of the piston.

28. A drawing press including a blank holder and means for resisting the movement of the blank holder, said means embodying a resiliently yielding element and a self-contained fluid pressure means both acting directly upon the blank holder, said fluid pressure means embodying a cylinder for containing fluid, said fluid being transferable back and forth to opposite sides of the piston, a valved passage for transferring the fluid from one side of the piston to the other, and means yieldingly seating the valve, said valve being adapted to be unseated against the stress of the last said means by fluid pressure.

29. A drawing press including a blank holder and means for resisting the movement of the blank holder, said means embodying a resiliently yielding element and a self-contained fluid pressure means both acting directly upon the blank holder, said fluid pressure means embodying a cylinder for containing fluid transferable back and forth to opposite sides of the piston, a valved passage for transferring the fluid from one side of the piston to the other, means yieldingly seating the valve, said valve being adapted to be unseated against the stress of the last said means by fluid pressure, and means whereby the fluid pressure necessary to open the said valve may be varied at will.

30. A drawing press including a blank holder and means for resisting the movement of the blank holder, said means embodying a resiliently yielding element and a self-contained fluid pressure means both acting directly upon the blank holder, said fluid pressure means embodying a cylinder for containing fluid transferable back and forth to opposite sides of the piston, a valved passage for transferring the fluid from one side of the piston to the other, means yieldingly seating the valve, said valve being adapted to be unseated against the stress of the last said means by fluid pressure, and means operating automatically for transferring the fluid back to the first recited side of the piston.

31. A drawing press including a blank holder and means for resisting the movement of the blank holder, said means embodying a resiliently yielding element and a self-contained liquid pressure means both acting directly upon the blank holder, said liquid pressure means embodying a cylinder for containing liquid, a valved passage for

transferring the liquid from one side of the piston to the other, means yieldingly seating the valve, said valve being adapted to be unseated against the stress of the last said

5 means by liquid pressure, and means operating automatically for transferring the liquid back to the first recited side of the piston, the last recited means embodying a passage through the piston and a spring controlled valve for controlling the last said

10 passage.

32. A drawing press including a blank holder, a resiliently yielding element reacting upon the blank holder for yieldingly resisting the movement thereof, and fluid under pressure greater than atmospheric against which the said blank holder also operates to be yieldingly resisted thereby, both said resiliently yielding element and the fluid

20 pressure means being disposed on the same side of the work, the said resilient element also operating to return the blank holder after the drawing operation.

33. A drawing press including a blank holder, means for resisting the movement of said blank holder and for maintaining a substantially unvarying pressure of the blank holder throughout substantially the entire stroke of the press, said means embodying a resiliently yielding element and fluid under pressure greater than atmospheric for also yieldingly resisting the move

ment of the blank holder and disposed on the same side of the work as the said element, and means for varying at will the pressure of one of the resistance creating means.

34. A drawing press including a blank holder, and means for maintaining a substantially unvarying pressure of the blank holder throughout substantially the stroke of the press, said means embodying two independent and different types of means each acting directly upon said blank holder for yieldingly resisting the movement of the blank holder and both disposed on the same side of the work, one only of said means being operable to return the blank holder.

35. A drawing press including a blank holder and means for resisting the movement of the blank holder, said means embodying a resiliently yielding element and a self-contained fluid pressure means both acting directly upon the blank holder for yieldingly resisting the movement of the blank holder, and both disposed on the same side of the work, and resiliently yielding means operating in opposition to the first recited resiliently yielding means for controlling the action of the said fluid pressure means.

In testimony whereof I have signed my name to this specification, on this 13th day of October, A. D. 1926.

JOHN NELSON.
